UNITED STATES PATENT OFFICE.

ALONZO HARRIS, OF MATTOON, ILLINOIS, ASSIGNOR OF ONE-HALF TO
OTTO SCHILLING, OF MATTOON, ILLINOIS.

JOURNAL-BOX HOIST.

No. 839,141.

Specification of Letters Patent.

Patented Dec. 25, 1906.

Application filed June 15, 1906. Serial No. 321,806.

To all whom it may concern:

Be it known that I, ALONZO HARRIS, a citizen of the United States, residing at Mattoon, county of Coles, and State of Illinois, have invented certain new and useful Improvements in Journal-Box Hoists, of which the following is a specification.

The object of this invention is to provide means for lifting a car-truck frame without the necessity for applying jacks or lifting-screws, which device is applicable to all styles of trucks and may be readily set up in position for use and which will be strong, durable, and easily applied and operated.

Another object of the invention is to obviate the possibility of injury to the truck mechanism by carelessness in the use of the device, and the final object is to simplify the construction and arrangement of the parts and increase the efficiency of the device correspondingly.

The invention consists in the features of construction and combination of parts hereinafter described and claimed.

In the drawings, Figure 1 is a side elevation of the device, showing the method of using the same; Fig. 2, a cross-sectional elevation showing the hoist in proximity to the rail, and Fig. 3 a top or plan view of the skid 30 with the shoe mounted thereon.

The hoist consists, essentially, of two parts—an incline or skid 1 and a slidable shoe 2. The incline or skid is preferably of I formation, having upper flanges 3 and lower flanges 4, and an intermediate web 5. Formed on the under face of the lower flanges are arranged a plurality of teeth or pins 6, which are suitably spaced to be inserted into adjacent ties. As shown, the skid or incline 35 is of sufficient length to bridge the distance between three ties, although the device may be longer or shorter, as desired, and the forward upper end 7 of the skid or incline is rounded to permit the shoe to slide over the end of the skid or incline without difficulty. The upper face of the incline is provided in its 40 center with a V-shaped groove 8, extending uninterruptedly from end to end of the skid or incline and being cut in the forward or 45 rounded end of the incline for a considerable 50 distance. The groove is adapted to receive a

V-shaped rib 9 on the under face of the shoe, and the shoe is provided at its forward end with a stop or abutment 10.

In use the device is positioned adjacent to 55 and outside of a rail by inserting the teeth or pins into the top surface of the adjacent ties, after which the truck-frame to be raised is brought into position for the journal-box to rest upon the top face of the shoe and abut 60 against the end stop, after which the truck is carried or drawn forward, which compels the forward travel of the shoe along the incline by reason of the contact of the stop or abutment against the journal-box, and this travel 65 of the shoe raises the shoe and the truck-frame supported thereby. The groove 9 extends from end to end of the incline or skid, and the forward or upper end of the groove is unobstructed, so that the shoe will slide 70 over the end of the skid or incline in case the truck is drawn forward too far, which permits the parts to drop into place without injury, and the curvature of the forward end of 75 the skid permits this sliding over or tilting of the shoe in an easy and gradual manner, which obviates all danger of breakage or injury. If the forward end of the slot or groove were obstructed or terminated back of the end of the skid or incline, an excess 80 movement of the truck would tend to tilt up the rear end of the skid or incline by reason of continued pressure against the forward end, and this tilting might have the effect of derailing the truck or causing serious injury. 85 By allowing the shoe to slide over in the manner indicated the danger of such derailing or injury is obviated and the value and efficiency of the device thereby increased.

What I regard as new, and desire to secure 90 by Letters Patent, is—

1. A journal-box hoist comprising an incline or skid having in its upper face an uninterrupted longitudinally-extending groove open at the forward end, and a shoe provided 95 with a rib adapted to travel in the groove, substantially as described.

2. A journal-box hoist comprising an incline or skid having in its upper face an uninterrupted longitudinally-extending groove 100 open at the forward end, a shoe provided with a rib adapted to travel in the groove,

and having a stop or abutment adapted to position a journal-box, substantially as described.

3. A journal-box hoist comprising an incline or skid having a rounded forward upper corner and having in its upper face a longitudinally-extending uninterrupted groove or channel conforming at its forward end to the curvature of the upper corner, in combination with a shoe provided with a rib adapted to travel in the groove, substantially as described.

4. A journal-box hoist comprising an incline or skid having a rounded forward upper corner and having in its upper face a longitudinally-extending uninterrupted groove or channel conforming at its forward end to the curvature of the upper corner, in combination with a shoe provided with a rib adapted

to travel in the groove and having in its forward end a stop or abutment adapted to position a journal-box, substantially as described.

5. A journal-box hoist comprising an incline or skid and a shoe adapted to travel on the upper face of the skid, one of the members being provided with a rib and the other with a groove, the rib and groove adapted to coact together to permit the uninterrupted travel of the shoe up the inclined skid and over the forward end thereof to prevent breakage in case of accident, substantially as described.

ALONZO HARRIS.
